 corporation of Alabama

Application June 3, 1936, Serial No. 83,344

6 Claims. (Cl. 66—172)

The object of this invention is to provide a stocking with a novel rib top having therein an integral all over elastic garter effect so that the stocking may be worn and kept in place on the 5 leg of the wearer without the need of using auxiliary garter means.

A further object of this invention is to provide the rib top with an inlaid rubber yarn extending spirally of the top throughout the entire length 10 thereof, the beginning and the end of the rubber yarn being fastened or anchored securely in the rib top.

A still further object of this invention is to make the rib top from a plurality of textile 15 yarns with a knitting spiral of a like plurality of courses, so that the rubber yarn inlay courses will be separated from each other by the plain knit rib courses.

In the drawing:

Fig. 1 is a view showing a man's half hose 20 containing my novel top and

Fig. 2 is a detail view of a portion of the top showing the knitted stitches.

It has been customary in providing garter top 25 socks or stockings to inlay a rubber yarn, known in the trade as rubber or "Lastex", uncovered or covered with a textile wrapping in successive rib courses on a single feed ribber for a number of courses, the number being relatively few in comparison to the number of courses in the entire 30 top. This rubber or elastic thread is usually placed near the upper edge of the top and extends for about a half to three quarters of an inch. It has been customary to make the socks of less than their normal length in the leg, as 35 with a normal length sock, the rubber insert provided would be positioned near the calf of the leg of the wearer and the insert was not effective at this point. Accordingly the socks were made shorter in the leg so that the garter 40 insert would be effective, on a narrower portion of the leg, in retaining the sock in position. Such short length socks are objectionable in that when the wearer crosses his legs the uncovered portion of his leg above the short sock is usually 45 brought into view, beneath the trouser legs. Furthermore the garter effect, produced by placing the inlay in successive rib courses for a short distance, is too tight and binds the leg. Again it stretches less than the remainder of the rib 50 top in which no rubber is incorporated. Apparently this cannot be overcome by placing less initial tension upon the rubber yarn, as then it extends in an unsightly manner from and between the wales of the rib top.

55

I have overcome the above objections and have provided a normal length sock in which there is an all over elastic garter effect in the rib top without the garter being too tight. I can if I desire make the sock of less or more than normal 5 length when it is necessary for style purposes. It is understood that my invention relates to the rib top and that the same may be used upon any type of stocking, hose or sock or that the same may be used in any manner in which a rib 10 top or like fabric may be used.

In Fig. 1 at 1 is shown a man's half hose having my novel top 2 thereon. It will be seen that the rubber yarn 3 extends spirally throughout the top 2 being anchored at points 4 and 5 in a 15 manner to be described.

In Fig. 2 the detail of the stitches shows that the top is made of separate yarns 6, 7, and 8 each fed at a separate feed on a three feed ribber. The knitting is done on a three course spiral, that is the courses comprising the entire top are knit of the separate yarns in regular and repeating the sequence on the three feed machine. Following the feed at which yarn 6 is knitted the rubber yarn 3 is laid in in the usual manner between the cylinder or plain stitches in wales 9, 10, 11, and 12 and the dial or rib stitches in wales 13, 14, 15, and 16. The knitting continues as shown in Fig. 2 with the rubber being inlaid for the entire rib top including the welt and the loose courses. The knitting is preferably done with a loose stitch to allow for expansion with the rubber. The tension on the rubber at the machine is adjusted so that the rubber yarn is under slight tension in 20 the finished rib top. I have disclosed the use of a three feed machine with the rubber every third course, but obviously a machine with a different number of feeds might be used, say two, or four, or even five textile yarn feeds with the rubber fed and inlaid at one or at more than one spaced feed. In such a case the rubber 25 course would be spaced in accordance with the number of textile yarn feeds used.

During the making of the welt the rubber 30 yarn is inlaid and the tuck stitches used in making the welt secure or anchor the rubber yarn at 4. When the successive tops are separated from each other, the rubber yarn is cut above the point 4.

As usual the rib top is transferred to the needles of a plain machine or footer to make the leg and foot of the stocking. This is done by transferring the loose course of the rib top to the needles of the footer and then ravelling back 35

the excess fabric to the loose course. Since the rubber yarn extends through and beyond the loose course, this also is removed during the ravelling and the loose end thereof may be allowed to draw back into the fabric to be held solely by and between the cylinder and dial wales and thereby anchored in the fabric at the point 5, in the course next adjacent the loose course.

10 Instead of locking in the ends of the rubber in the welt and in the first course from the loose course, the ends of the rubber may terminate below the welt and above the loose course, say a course or two before the welt and the loose course. In this event the ends of the rubber will be anchored by interknitting with the fabric for a few stitches by means well known to the trade.

15 It will be apparent that I have provided a novel rib top for hosiery and that the same may be modified or changed without departing from the spirit of my invention as defined in the scope of the appended claims.

I claim:—

20 1. A tubular stocking having a single wall rib top and a single course spiral plain leg said top comprising courses containing plain and rib wales, said courses being knit of separate yarns in regular and repeating sequence, and a spiral elastic thread inlay between the plain and rib wales only in the courses knit of one of said 25 yarns substantially throughout the top.

25 2. A tubular stocking having a single wall rib top and a single course spiral plain leg said top comprising courses containing plain and rib wales, said courses being knit of at least three separate 30 yarns in regular and repeating sequence, and a spiral elastic thread inlay between the plain and rib wales only in the courses knit of one of said 35 yarns substantially throughout the top.

30 3. A tubular stocking having a single wall rib

top and a single course spiral plain leg said top comprising courses containing plain and rib wales, said courses being knit of separate yarns in regular and repeating sequence, and a spiral elastic thread inlay between the plain and rib wales only in the courses knit of one of said 5 yarns substantially throughout the top, one end of the elastic thread being secured in the welt courses of the rib top.

35 4. A tubular stocking having a single wall rib top and a single course spiral plain leg said top comprising courses containing plain and rib wales, said courses being knit of separate yarns in regular and repeating sequence, and a spiral elastic thread inlay between the plain and rib 10 wales only in the courses knit of one of said yarns substantially throughout the top, one end of the elastic thread being secured at the upper end of the rib top.

40 5. A tubular stocking having a single wall rib top and a single course spiral plain leg said top comprising courses containing plain and rib wales, said courses being knit of separate 20 yarns in regular and repeating sequence, and a spiral elastic thread inlay between the plain and rib 25 wales only in the courses knit of one of said yarns substantially throughout the top, one end of the elastic thread being secured at the lower end of the rib top.

45 6. A tubular stocking having a single wall rib top and a single course spiral plain leg said top comprising courses containing plain and rib wales, said courses being knit of separate 30 yarns in regular and repeating sequence, and a spiral elastic thread inlay between the plain and rib 35 wales only in the courses knit of one of said yarns substantially throughout the top, one end of the elastic thread being secured at the upper end of the rib top and the other end being secured at the lower end of the rib top.

40 ROBERT E. DAVIS.
